UNITED STATES PATENT OFFICE.

EDOUARD DE VLIEGER, OF BRUSSELS, BELGIUM.

GARMENT-SUPPORTING WAIST.

No. 836,566.

Specification of Letters Patent.

Patented Nov. 20, 1906.

Application filed April 28, 1905. Serial No. 257,885.

To all whom it may concern:

Be it known that I, EDOUARD DE VLIEGER, a subject of the King of Belgium, residing at 76 Boulevard du Nord, Brussels, in the Kingdom of Belgium, have invented certain new and useful Garment-Supporting Waists, of which the following is a specification.

The object of this invention is to provide a waist having secured thereto bands of any convenient material and of improved form and to the ends of which are movably connected elastic bands.

A further object of the invention is to provide a waist having garment-supporting bands secured thereto and with a continuous band from one side of the waist adjacent the neck and down upon the other side, with a central band occupying substantially a vertical position along the back.

20 A further object of the invention is to provide a waist with bearing-bands arranged along the sides and across the neck and down the back, with bracing and strengthening bands arranged obliquely thereto.

25 With these and other objects in view the invention comprises certain novel constructions, combinations, and arrangements of parts, as will be hereinafter fully described and claimed.

30 In the accompanying drawings, Figure 1 is a view in elevation of the inside of the improved waist shown in folded position. Fig. 2 is a view in elevation of the inside of the improved waist shown in an extended position. Fig. 3 is a view in elevation of a modified form of the improved waist shown in extended position and embodying obliquely-disposed brace-bands.

35 Like characters of reference designate corresponding parts throughout the several views.

40 In its simpler form, the garment comprises a waist *b*, which may be with or without sleeves and is here shown for simplicity and clearness of illustration without sleeves. To one side of the waist is secured in any approved manner the bearing-bands *a*, extending upward along one side across between the neck and shoulders and downward upon the opposite side and attached to the waist-body

throughout the greater portion of its length, as from *c* to *c*. (Shown especially in Fig. 2.) The ends of the band *a* are turned upward to form loops *d* and held in adjustable position by means of slides or buckles *b* of any approved form. Through the loops *d* are secured elastic bands *f* of the usual and approved form. Along substantially the middle of the back of the garment, and extending in a normally vertical position, is a band *a'*, 50 having its lower end folded upward to form the loop *d'*, similar to the loops *d* and similarly held by the slide or buckle *e'*, the said band being secured to the waist throughout the greater portion of its length, as from its upper end to about the point *c'*.

In the form shown in Fig. 3 the bands *a* and *a'* are arranged similar to the bands in Figs. 1 and 2, and thereto is secured strengthening-bands comprising the bands *a²*, secured 70 about the edges of the armholes, with bands *a³* extending from the said bands *a²* along the shoulder-seam to and connected with the band *a*. From adjacent the junction of the bands *a³* with the band *a* oblique bands *a⁴* extend downwardly to and connected with the band *a'* intermediate its ends, and from adjacent each point of junction bands *a⁵* extend obliquely across the back, forming a junction with the bands *a²* at the back of the armholes. 75 From the bands *a²* bands *a⁶* extend obliquely to the band *a*, forming a brace from the front side of the armhole to the band *a*. It is to be understood that the bands *a* and *a'* and their several associated bands may be secured upon 80 the outer side of the garment, as shown in Fig. 1, or upon the inside of the garment, as shown in Fig. 2, but are preferably secured upon the outside of the garment, as shown in Fig. 3, with the ends inserted through openings *g* to position the elastic ends or bands *f* and *f'* upon the inside of the waist.

85 What I claim is—

A waist comprising a body portion having a bearing-band extending from the middle of 90 the back adjacent the neck downward along each side and secured upon each side to a point intermediate the top and bottom, a band secured along the middle of the back 95 and secured at its top end to the middle point 100

of the first band, loops formed in the lower ends of said bands, adjusting-buckles slidably secured upon the said bands and to adjust the size of the loops, elastic straps slidably inserted through the loops, and obliquely-disposed brace-bands extending between the two bands above mentioned.

In testimony whereof I have signed my name to this specification in the presence of two subscribing witnesses.

EDOUARD DE VLIEGER.
